UNITED STATES PATENT OFFICE.

JOHN H. GAVIN, OF CHICAGO, ILLINOIS, ASSIGNOR TO L. WOLFF MANUFACTURING COMPANY, OF CHICAGO, ILLINOIS, A CORPORATION OF ILLINOIS.

LAVATORY WASTE-PLUG.

1,208,770.

Specification of Letters Patent. Patented Dec. 19, 1916.

Application filed June 25, 1914. Serial No. 847,198.

To all whom it may concern:

Be it known that I, JOHN H. GAVIN, a citizen of the United States, residing in Chicago, in the county of Cook and State of Illinois, have invented a new and useful Improvement in Lavatory Waste-Plugs, of which the following is a specification.

This invention relates to improvements in lavatory waste plugs.

In installing lavatories, bath tubs and the like, it is often found that the same have certain irregularities resulting from the manufacture which renders it difficult to make easy connections between the waste or drain plugs and the drain pipes and other piping. Lavatories made of cast iron, porcelain, vitreous material or other substances requiring molding casting or baking, shrink or are otherwise so distorted in the manufacture that the surfaces between which the plugs are clamped, are not parallel. It sometimes also happens that in attaching a lavatory to a wall, the lower surfaces of the lavatory do not extend perpendicularly from the wall. The result is that the tail-pieces of the plugs are not arranged vertically or in line with the waste-pipes to which they must be connected. These defects have proved difficult of correction in actual practice and have given rise to a great deal of trouble in the installation of the plumbing fixtures. Nor is it possible to overcome the inherent defects in the lavatories, bath-tubs and the like by any known methods of manufacture.

The object of my invention is to provide simple means whereby the waste plugs may be attached to the lavatories, bath-tubs and the like in such a way that the tail-piece or portion to be connected to the waste pipe or drain pipe, may be always alined with the latter regardless of any unevenness or irregularities in the lavatory or tub.

The invention furthermore consists in the improvements in the parts and devices and novel combinations of the parts and devices herein shown, described or claimed.

In the drawing forming a part of this specification, Figure 1 is a vertical, sectional

view of a portion of a lavatory and my improved plug. Fig. 2 is a vertical, sectional view of parts of the plug proper; Fig. 3 is a detail, horizontal, sectional view taken substantially on the line 3-3 of Fig. 1, and Fig. 4 is a view similar to Fig. 1 showing a somewhat modified form of the construction.

In said drawing 10 denotes the bottom wall of the lavatory which may be made of cast iron, porcelain, vitreous material or other substance commonly used. In said bottom wall, as usual, is provided the drain outlet 11 and said lavatory is also provided with the usual overflow passageway 12, the lower wall of which is provided with an opening 13 in alinement with the opening 11.

The improved plug consists of an upper, hollow member 14 having a flange 15 adapted to seat on a correspondingly inset portion 16 of the bottom of the lavatory, putty or cement or other substance 17 being placed therebetween to form a water-tight joint in the usual manner. The member 14, at the bottom thereof, is provided with a pair of downwardly extending pivot lugs 18, 18, 75 diametrically arranged, to which is pivoted a shell 19, the latter having a pair of correspondingly upwardly extending pivot lugs 20 and the two parts being pivotally connected by rivets 21 or other suitable means. 80 As shown in Figs. 1 and 2, the members 14 and 19 are so formed or cut away that recesses or openings 22, 22 are provided adjacent the pivotal connections and, as will be understood by those skilled in the art, 85 these openings will be placed in alinement with the overflow passageway 11 so that water flowing therethrough will pass freely into the shell 19. In other words, the axis of the pivotal connections between the members 14 and 19 will extend transversely of the overflow passageway 11. The shell 19 is exteriorly threaded, as indicated at 22', so that it is adapted to receive a lock-nut 23 having a concave face 24 coinciding with a portion of the surface of a sphere, the center of which lies midway between the two pivotal connections 21, 21. Interposed between

95

the lock-nut 23 and the bottom wall 12 of the overflow are two washers, an upper rubber washer 25 and a washer 27 having a convex, curved surface 28 formed to correspond and coöperate with the curved face 24 of the lock-nut 23. The washer 27 and lock-nut 23, with their convex and concave surfaces form a ball-joint, as will be understood. The lock-nut 23 is provided with a depending flange 29 exteriorly threaded and adapted to receive the tail-piece 30 which, as will be understood, is attached at its lower end to the waste pipe proper.

In the embodiment of the invention shown in Figs. 1 and 3, the lock-nut 23 and the washer 27 are formed of sheet metal, the lock-nut having the hexagonal contour shown in Fig. 3 located beneath the end of the shell 19 and extending upwardly in threaded engagement therewith and terminating in the spherically curved portion or end 32 to provide the curved surface 24. The washer 27 consists of a single piece of sheet metal having an upwardly extending flange 33 and an outwardly extending spherically curved portion 34 adapted to rest upon and move over the curved surface 24 to form the ball-joint already mentioned. The upper rubber washer 25 is inserted between the adjacent face of the bottom wall 10 of the lavatory bowl or other article and the washer 27.

The construction shown in Fig. 4 differs only from that already described, in that the lock-nut consists of a relatively short annular lock-nut 40 having a curved surface 41 which is engaged by a washer 42 of solid metal having a correspondingly curved face 43. Between the washer 42 and the under surface of the bowl, a rubber washer 45 is positioned. The shell 19, near its upper end, is provided with an inwardly extending bead or rib on which is adapted to be loosely seated a strainer.

From the preceding description, it will be seen that my improved plug may be adjusted to compensate for any irregularities in the lavatory surfaces between which the plug must be clamped, it being understood that the shell 19 is of less outside diameter than the opening 13 and the openings in the washers 25, 26 and 27, thus allowing free movement of the shell 19 with respect to said last named parts. With the combination of the pivotal connection between the members 14 and 19 and the ball-joint between the lock-nut and washer 27, a substantially universal adjustment is provided which will enable the tail-piece 30 to always be brought in vertical axial alinement with the drain-pipe proper.

Although I have herein shown and described what I now consider the preferred embodiment of my improvement, yet it will be understood that various changes and

modifications may be made without departing from the spirit of the invention, and all such changes and modifications are contemplated as come within the scope of the claims appended hereto.

70

I claim:—

1. A plug for lavatories and the like comprising two pivotally connected hollow members, the lower of said members being threaded, a ball-joint washer, and a coöperating ball-joint lock-nut, the latter coöperating with said threaded member and the washer being interposed between the nut and the surface against which the plug is to be clamped, substantially as specified. 80

2. A plug for lavatories and the like comprising two hollow members pivotally connected, said members being recessed adjacent the pivotal connections, and means for clamping said members in position, said means including a lock-nut and washer having a ball-joint therebetween, substantially as specified. 85

3. A device of the character described including, in combination: a lavatory having an overflow passageway, the bottom wall of the lavatory proper and the bottom wall of the overflow passageway having aligned openings; a plug extending through said openings, said plug comprising an upper flanged member and a lower threaded member pivotally connected, said members being cut away on the side adjacent the overflow passageway; and means for clamping the plug in place, said means including members having a ball-joint therebetween, substantially as specified. 90

4. A device of the character described including, in combination: a lavatory having an overflow passageway; a plug extending through the bottom wall of the lavatory and overflow passageway; and means for clamping said plug in position and permitting the latter to have a universal adjustment with respect to the lavatory, the contact between interengaging surfaces being substantially constant in all adjustments, substantially as specified. 105

5. A plug for lavatories and the like comprising two hollow members adjustably connected, one of said members being exteriorly threaded, a lock-nut coöperating with said threaded member, and a washer coöperating with said lock-nut, the washer and lock-nut having coöperating curved surfaces forming a ball-joint, the contact between interengaging surfaces being substantially constant in all adjustments, substantially as specified. 115

6. A plug for lavatories and the like comprising two hollow members adjustably connected, one of said members being externally threaded, a lock-nut consisting of a single piece of internally threaded sheet metal engaging said externally threaded hollow member, and a washer of sheet metal 125

130

coöperating with said lock-nut, the adjacent edges of said washer and lock-nut being curved to provide coöperating surfaces forming a ball-joint, the contact between intervening surfaces being substantially constant in all adjustments, substantially as specified.

Signed this 20th day of June, 1914, in the presence of two subscribing witnesses.

JOHN H. GAVIN.
